UNITED STATES PATENT OFFICE

152,613

DESIGN FOR A TEXTILE FABRIC OR SIMILAR ARTICLE

Eugene Irving Hanson, New York, N. Y.

Application January 28, 1948, Serial No. 144,116

Term of patent 3½ years

(Cl. D92—1)

To all whom it may concern:

Be it known that I, Eugene Irving Hanson, a citizen of the United States, residing in New York, county of New York, and State of New York, have invented a new, original, and ornamental Design for a Textile Fabric or Similar Article, of which the following is a specification, reference being had to the accompanying drawing, forming part thereof.

The figure of the drawing is a plan view of the textile fabric showing my new design.

The dotted lines outline a design unit which unit is repeated over the fabric in regular succession as indicated by the extensions beyond the unit boundaries.

I claim:

The ornamental design for a textile fabric or similar article, as shown and described.

EUGENE IRVING HANSON.
